UNITED STATES PATENT OFFICE.

STEFANO BATTILANI, OF NEW YORK, N. Y.

SHOE-TREE.

Application filed April 15, 1926. Serial No. 102,179.

The invention relates to a shoe tree and has for its object to provide a shoe tree with a flexible arched toe piece adapted to conform with the contour of the fore part of the 5 shoe and having rearwardly extending portions or portion to engage with the rear part of the shoe, said rearwardly extending part or parts being likewise flexible.

A device is produced which will naturally 10 take the shape of the shoe and will insure in a very careful way maintaining the original form of the shoe and will not force the shoe to conform to the shape of the shoe tree. The improved shoe tree is very efficient in its 15 operation and self adjustable to different sizes of shoes.

Other objects and attendant advantages will be apparent from the following detailed 20 description of my invention and in the appended claims.

Referring to the drawings in which preferred embodiments of the invention are illustrated:

Fig. 1 is a side elevation of my improved 25 shoe tree, showing it in place in a shoe, the shoe being indicated in broken lines,

Fig. 2 is a longitudinal sectional view showing a slightly different form,

Fig. 3 is a cross sectional view taken on 30 the line 3—3 of Fig. 2,

Fig. 4 is a fragmentary detail bottom plan view showing a means of attaching the flexible rearwardly extending member to the toe piece,

Fig. 5 is a detail cross sectional view taken 35 on the line 5—5 of Fig. 4,

Fig. 6 is a side view of a modified form,

Fig. 7 is a top plan view of the form shown in Fig. 6, and,

Fig. 8 is a side view of another form.

Referring again to the drawings, the reference numeral 10 designates the flexible arched toe piece. This member is constructed of comparatively thin springy material 45 such as celluloid, fibre, sheet metal, etc., and has a rearwardly extending part 11 which engages with the back part of the shoe.

The flexible arched toe piece is formed with the inturned portions or flaps 12. The 50 material being of a very flexible nature this toe piece will readily conform itself to the contour of the fore part of the shoe to shoes of numerous different widths or sizes. The flaps 12 may extend only a very short distance along the sides of the toe piece or

they may stop at any desired point along the sides thereof. They may likewise extend inward any desired distance. It may also be advisable to make the flaps or the body of the toe piece of materials having varying 60 degrees of flexibility.

As illustrated in Fig. 1 the rearwardly extending member or portion 11 may be made entirely of a flexible material or it may have a flexible coiled part 13 at the rear end to 65 abut against the back part of the shoe. This coiled part 13 may be made more flexible than the rest of the member 11 or any part of said member 11 may be made more or less flexible. This coiled part 13 or the 70 flexibility of the entire member 11 will take care of shoes of various lengths and will always force the arched toe piece in its desired position with a gentle pressure just sufficient to maintain the shoe in its original 75 shape and not force it to conform to the shape of the shoe tree as practically all of these devices do on account of their positive action.

In Fig. 2 the rearwardly extending part 11 80 is secured at 14 to the toe piece and while, as described in Fig. 1 the entire member may be flexible, in this form the part 13^a particularly compensates for variations in the lengths of different shoes. The rear part 15 rests 85 against the rear part of the shoe and keeps the toe piece in place. The extension 11 may be made of the same material and integral with the toe piece or it may be made of a different material and rigidly or otherwise 90 secured to the toe piece.

It may be desirable in some forms to have the flexibility entirely in the arched toe piece and have the member 11 stiff or with very little flexibility or on the other hand it may 95 be advantageous to have the arched toe piece fairly rigid or with very little flexibility and have the member 11 very flexible.

In order to make the toe piece more flexible I may cut slots or openings as indicated 100 at 16. These openings may run crossways or lengthwise or in any desired direction.

Figs. 4 and 5 illustrate a method that might be employed if it is desired to make the toe piece and the rearwardly extending 105 member separate. The fore part of the rearwardly extending member may be tapered as shown at 17 and engage a tapered hole in a piece 18 secured to the under side of the toe piece.

Figs. 6 and 7 illustrate an alternate form in which two rearwardly extending portions 11^b project from the toe piece 10. This toe piece is arched and formed of flexible material as shown in Fig. 1 and has the in-turned portions 12. In this form the ends 19 are curved inwardly and abut against the rear part of the shoe. The extensions 11^b may be made entirely of flexible material or they may have flexible parts 20 at some suitable location. These flexible parts 20 may be made of the same material as the members 11^b or they may be made of different material and secured to said members. 15 When this form is inserted in a shoe the flexible parts 20 will be forced together and the entire length of the members 11^b will be gently pressed against the sides of the shoe and keep the shoe in its proper shape. 20 Fig. 8 shows the toe piece 10 as being formed of the same material as the rearwardly extending member 11. The toe piece in this form may be of a fairly rigid construction and the flexibility be entirely in 25 the member 11. An additional flexible loop 13^c may be provided in this member 11. As illustrated this loop is shown as a complete circle in order to give great flexibility and it may be made in any desired way. The 30 part 13^c might be the same as the parts 20 in Fig. 7 or parts 20 in Fig. 7 might also be constructed as 13^c in Fig. 8.

As previously explained it will be obvious from the foregoing that this improved shoe 35 tree will keep the shoe in its original form and will not force the shoe out of shape as most of the shoe trees now in use do. The device will readily conform to sizes of shoes within wide limits, is simple and easy to 40 manufacture.

The shoe tree may be made of any desired material as long as it has the necessary 45 flexibility. It may be partly or entirely ornamented in any way or covered with silk or cloth or a coating of any desired nature. While it is primarily intended for use as a shoe tree it can readily be seen that it 50 may be used as a form to display shoes for inspection or sale. It may be made of any 55 desired height or width to suit different styles of shoes. While a high heeled slipper is illustrated and the part 11 is therefore raised up quite substantially it is obvious that in a tree for a low heeled shoe it would be advantageous to have the parts 11 ex-

tend rearwardly in substantially the same plane as the toe piece.

The flaps 12 might extend rearwardly as illustrated in Fig. 8. In this way the sides of the shoe will be given additional support 60 when the shoe tree is in place in the shoe.

The slots or openings shown in Fig. 2 give an additional advantage in that they permit the restriction of the toe piece when the shoe tree is being used for very narrow 65 shoes or for taking care of the shapes in right and left hand shoes.

While I have described preferred embodiments of my invention I wish it to be understood that numerous changes may be made 70 in details or form without departing from the spirit of the invention as set forth in the appended claims.

What I desire to claim is:

1. A shoe tree comprising, a flexible 75 arched toe piece having inturned flaps on each of its sides, said inturned flaps being curved in cross section and adapted to rest against the inner sole of the shoe and cause said toe piece to gently conform with the 80 contour of the fore part of the shoe, and a rearwardly extending member to engage with the rear of the shoe, said member being flexible.

2. A shoe tree comprising, a flexible 85 arched toe piece having inturned flaps on each of its sides, said inturned flaps being positioned away from the front end of the toe piece and being curved in cross section and adapted to rest against the inner sole 90 of the shoe and cause said toe piece to gently conform with the contour of the fore part of the shoe, and a rearwardly extending member to engage with the rear of the shoe, said member having flexible portions there- 95 in.

3. A shoe tree comprising, a flexible arched toe piece having inturned flaps on each of its sides, said inturned flaps being curved in cross section and adapted to rest 100 against the inner sole of the shoe and cause said toe piece to gently conform with the contour of the fore part of the shoe and having slots suitably placed therein so as to insure greater flexibility, and a rear- 105 wardly extending member to engage with the rear of the shoe, said member being flexible.

In testimony whereof I affix my signature.
STEFANO BATTILANI.
